UNITED STATES PATENT OFFICE

2,642,248

SUCTION FASTENING DEVICE

William P. Semon, Manhasset, N. Y.

Application January 26, 1951, Serial No. 208,029

1 Claim. (Cl. 248—206)

1

This invention relates to a suction fastening device for holding parts together in apposition or for securing an article to a supporting surface.

The invention has in view a suction fastening device which is adapted to be secured to and to cover an extended area of a supporting body for holding parts thereof in adjacent relation or for supporting an article thereby and which is constructed and arranged to permit of the convenient removal of the fastening device from the supporting body.

More particularly, the invention comprehends a suction fastening device consisting of a flexible resilient member having a plurality of vacuum cups on one face thereof which are provided with apertures opening into the vacuum cups and through the outer face of said member together with an impervious backing adhesively secured to said member in sealing relation with the outer ends of said apertures and which backing is adapted to be removed for breaking the suction created by the vacuum cups.

Still another object of the invention is to provide a suction fastening device of said character in strip or elongated formation in which the vacuum cups are integrally formed therewith and disposed in longitudinally spaced rows to permit of the same being secured on opposite sides of a parting in a body to hold the opposite edges thereof in apposition.

With the foregoing and other objects in view, reference is now made to the following specification and accompanying drawings in which the preferred embodiments of the invention are illustrated.

In the drawings:

Fig. 1 is a plan view of a suction fastening device constructed in accordance with the invention and illustrating the same with two rows of vacuum cups.

Fig. 2 is a longitudinal sectional view taken approximately on line 2—2 of Fig. 1.

Fig. 3 is an enlarged transverse sectional view taken approximately on line 3—3 of Fig. 1.

Fig. 4 is a plan view of a suction fastening device constructed in accordance with the invention and having means for fastening an article thereto.

Fig. 5 is a side view thereof.

Referring to the drawings by characters of reference, the suction fastening device illustrated in Figs. 1 to 3 thereof consists of a flexible elastic strip 10 having a plurality of vacuum cups 11 formed integrally therewith and projecting outwardly from one face thereof. The vacuum cups 11 are relatively closely spaced and have their

2

outer edges 12 disposed in a common plane parallel with the strip 10. The strip 10 is formed with apertures 13 which open through the outer face thereof and through the opposite face into the cups 11 at the center thereof.

In order to normally retain the apertures 13 in closed formation, an air impervious flexible backing 14 is adhesively secured to the outer face of the strip 10 in covering relation with the apertures 13. The backing 14 may be fashioned of any preferred air impervious material such as rubberized sheeting which is secured to the strip 10 by a gum adhesive which retains its adhesive quality for a long period of time and will secure the backing to the strip so as to retain the suction created by the vacuum cups. The backing 14 extends beyond the end of the strip 10 whereby the same may be conveniently grasped for removing the backing therefrom as illustrated in Fig. 2 of the drawings to thereby admit air into the vacuum cups through the apertures 13. The strip 10 may thus be readily removed from the supporting body without exerting a pull to break the suction produced by the vacuum cups. As illustrated, this form of fastening device includes two parallel rows of vacuum cups which are spaced apart so that the strip may be applied in covering relation with a parting such as a cut or incision A in a body B to hold the opposite edges of the parting in apposition.

In the modified form of the invention illustrated in Figs. 4 and 5 of the drawings, the fastening device is adapted for use for supporting articles hung thereon. For such use the backing 20 is provided with a plurality of hooks 21 secured thereto in longitudinally spaced relation, the backing having a slow-drying adhesive on the inner face thereof which is disposed in covering relation with the openings 22 in the flexible elastic strip 23 and which open through the opposite faces thereof centrally of the suction cups 24. The flexible elastic strip 23 is adapted to be secured by the suction cups to any desired supporting surface with the hooks 21 projecting outwardly from the backing 20 for receiving articles hung thereon.

What is claimed is:

In a suction fastening device, an elongated strip of flexible elastic material having a plurality of suction cups formed integrally therewith and projecting outwardly on one side thereof with the outer edges of the cups disposed in a common plane, said strip having apertures opening through the outer face thereof and through the inner face centrally of said cups respectively, and

an air impervious backing secured to the outer face of said strip by a slow-drying gum adhesive in sealing relation with said apertures and to permit of the removal thereof so as to break the suction created by the said cups when said cups are pressed against a supporting surface.

WILLIAM P. SEMON.
